DESIGN FOR A DRESS

Norman E. Debus, New York, N. Y.

Application July 19, 1941, Serial No. 102,224

Term of patent 3½ years

To all whom it may concern:

Be it known that I, Norman E. Debus, a citizen of the United States, residing in New York city, in the county of New York and State of New York, have invented a new, original, and ornamental Design for a Dress, of which the following is a specification, reference being had to the accompanying drawing, forming part thereof.

I claim:

The ornamental design for a dress, substantially as shown.

NORMAN E. DEBUS.
